UNITED STATES PATENT OFFICE.

EVELYN BUFFUM, OF CHICAGO, ILLINOIS.

DESIGN FOR A HAT-PIN HOLDER.

SPECIFICATION forming part of Design No. 35,905, dated May 13, 1902.

Application filed March 15, 1902. Serial No. 98,449. Term of patent 3½ years.

To all whom it may concern:

Be it known that I, EVELYN BUFFUM, a citizen of the United States, residing in Chicago, county of Cook, and State of Illinois, have invented and produced a new and original Design for Hat-Pin Holders, of which the following is a specification, reference being had to the accompanying drawings, forming a part thereof.

10 Figure 1 is a perspective view of my design for a hat-pin holder. Fig. 2 is a vertical side elevation of the same.

As shown in the drawings, the leading, important, and material feature is the presentation produced by my hat-pin holder, the same being the form of a harp.

My design consists of a base A, consisting of a series of steps with curved rises a. This base supports a rear standard B, having a plain face b. The back of the standard in cross-section presents a circular outline, and the upper part is bent forward and joined to the forward standard C. This has a series of beads along the inner edge D. At the top

and bottom of the forward standard C is a wreath d and d', the ends of which are secured by a lover's knot d² and d³. Below the wreath d and above the wreath d' on the forward standard C is a triangular protuberance E and E', whose sides are a series of corrugations e, said corrugations being convex in cross-sections. The end F of the rear standard is left plain to contain a monogram f, the complete design presenting the shape of a harp.

Having described my invention fully, what I regard as new, and desire to secure by Letters Patent, is—

The design for a hat-pin holder as herein shown and described.

In testimony whereof I have signed my name to this specification in the presence of two subscribing witnesses.

EVELYN BUFFUM.
